[57] **CLAIM**

The ornamental design for a chair, substantially as shown and described.

DESCRIPTION

FIG. 1 is a perspective view of a chair in accordance with the present invention as seen from the front and somewhat above the chair;

FIG. 2 is a side elevation of the chair as seen from the right of FIG. 1, the opposite side elevation being the same;

FIG. 3 is a side elevation of the chair in a recline position, the opposite side elevation in such position being the same;

FIG. 4 is a front elevation of the chair as seen from the left of FIG. 2;

FIG. 5 is a rear elevation of the chair as seen from the right of FIG. 2; and

FIG. 6 is a top plan view of the chair as seen from the top of FIG. 2.

FIG. 5

FIG. 6
